UNITED STATES PATENT OFFICE.

WILLIAM GOLDMAN AND BENJAMIN GLEICH, OF BROOKLYN, NEW YORK.

VALVE FOR CLOTHES STEAMING AND PRESSING APPARATUS.

Application filed October 17, 1925. Serial No. 62,990.

Our improvements relate exclusively to the type of valve used in conjunction with clothes steaming and pressing machines, and particularly to those connected with the 5 pressheads thereof, and controlling the admission of steam to the presser plate chambers thereof, in a manner heretofore well known in the art, our object being to simplify the construction and operation of such 10 steam valves, to render the same more effective and convenient of manipulation, and especially to facilitate the replacement of parts thereof at a minimum of cost, both of parts, time and labor involved, as herein 15 after explained,—the invention consisting essentially in the specific construction, combination and arrangement of component parts and appurtenances described and claimed, whereby these and other advan- 20 tageous results are attained as set forth.

In the accompanying drawings we illustrate a practical embodiment of the essential features of our invention in a valve applied to the presserhead of clothes steaming and 25 pressing apparatus of the character designated, although we do not limit ourselves to the identical form and construction of parts shown herein by way of exemplification, since changes may be made in minor details, 30 and equivalent mechanical expedients resorted to, with like results, and without departing from the spirit and intent of our invention in this respect.

With this understanding:—

Fig. 1, represents a right hand end elevation of a steaming and pressing machine, the presshead of which is equipped with our improved steam valve;

Fig. 2, is an elevation of the valve taken 40 at right angles to Fig. 1, but upon a larger scale, showing the adjacent portion of the presshead in section;

Fig. 3, is a top view of the valve and part of the presshead as shown in Fig. 2;

Fig. 4, is a sectional elevation taken upon plane of line 4—4, Fig. 3, showing the valve closed;

Fig. 5, is a view like unto Fig. 3, but with the valve stem handle turned to open the 50 valve and admit steam from the steam chest to presser plate chamber;

Fig. 6, is a sectional elevation taken upon plane of line 6—6, Fig. 5, showing the valve in open position;

Fig. 7, is a section of the tubular valve

casing taken upon plane of line 7—7, Fig. 6, but on a larger scale;

Fig. 8, is a section taken upon plane of line 8—8, Fig. 7;

Fig. 9, is a face view of the valve;

Fig. 10, is a sectional elevation thereof taken upon plane of line 10—10, Fig. 9;

Fig. 11, is an upper end elevation of the valve stem;

Fig. 12, is a detail view of the inner end 65 of the valve stem handle.

Fig. 1, shows the stationary buck B, so called, and the presshead P, pivotally mounted on the frame F, with relation thereto in the usual manner, steam being 70 supplied to the steam chest p, of said presshead through pipes p', which also function as supporting arms for the presshead, connecting it with the steam supply pipe p", upon the horizontal branch of which they 75 are fulcrumed. p", is the handle by means of which the presshead is manipulated; and p', the perforated presser plate on the under- 80 side of the presshead and spaced from the bottom of the steam chest p, to form the steam-distributing outlet chamber p", as indicated more particularly in Figs. 2, 4 and 6, of the drawings.

C, is a tubular valve casing which extends through the steam chest p, screwing into the 85 bottom thereof, as shown in said last mentioned figures of the drawings, the lower extremity of said tubular valve casing C, opening into the steam distributing outlet chamber p".

The upper extremity of said tubular valve casing is formed with a head c, female screw threaded for engagement with the corresponding male screw thread on the base of the cap member K, which latter functions not only as a closure to said tubular valve casing, but also as a fixed nut for the valve-controlling screw s, on the valve stem S, the upper portion of said cap member K, also constituting the stuffing box k, for the upper portion of said valve stem S, in conjunction with the packing k', and crown nut k", as shown more particularly in Figs. 4 and 6, of the drawings.

The tubular valve casing C, below its head c, is screw threaded peripherally for engagement with a binding nut b, for the compression of a packing ring b', between its lower portion and the opposed upper surface of the presshead P, thereby sealing 105 110

the aperture in the top of the presshead through which the valve casing C extends against steam pressure within the chest p.

The valve stem S, below the valve-controlling screw s, is formed with an annular shoulder s', which, by bearing against the seating surface k³, of the cap member K, adjacent to the aforesaid female-screw threaded portion thereof, when the valve is in open position as in Fig. 6, of the drawings, thereby functions as a stop to the tension of the retractile spring R, connected with the valve stem handle H, and likewise obviates possibility of steam passing the screw threads to the stuffing box k, above, and thereby preventing deterioration of packing and insures its integrity and utility as compared with the old form of valve which our present form is designed to supersede, the necessity for frequent renewal of valve stem packing in said older form of valve resultant from steam pressure being a serious practical objection thereto.

The upper, outer extremity of the valve stem S, is reduced in thickness to form an annular seat s², for the inner end of the valve stem handle H, and also formed with an angular (preferably square) stud portion s³, for the correspondingly shaped mortise h, in said inner end of the handle, the extension s⁴, of stem beyond said stud portion s³, being cylindrical and screw threaded for the reception of the binding nut s⁵, by means of which the handle H, is secured in position on said valve stem S, reference being had in this connection more particularly to Figs. 11 and 12, of the drawings in conjunction with Figs. 4 and 6, thereof.

The handle H is connected by means of a retractile spring R with a bracket arm K', which is rigidly attached to the cap member K, said spring R tending constantly to turn and hold the handle H, and valve stem S, in normal retracted position to close the valve v, which is swivel-mounted on the lower inner end of the stem S, against its seat c', the latter forming an integral part of the tubular valve casing C, as shown more particularly in Figs. 4, 6, 7 and 8, of the drawings.

The valve v, is swivel-mounted, on its stem S, by means of a coupling sleeve v', screw-connected with the shank of the valve and formed with an inturned annular shoulder engaging with an annular flange on the lower extremity of the valve stem, as shown in Figs. 4 and 6, of the drawings,—this form of copulation admitting of rotative movement of the valve stem S, with a minimum of disturbance and wear of the valve v.

The valve seat c', forms part of the transverse partition c², of the tubular casing C, being integral therewith, as will be seen by reference more particularly to Figs. 7 and 8, of the drawings which show the structure

of this part of the tubular casing in detail, said partition c², being formed with a steam passage c³, which communicates with the port c⁴, of the valve seat c'. When the valve v, is raised from its seat c', steam from the chest p, passes through said passage c³, and through the valve port c⁴, and thence down through outlets c⁵, c⁶, in the partition c², into the lower portion c⁶, of the casing and from thence to the steam-distributing chamber p⁴, and perforated presser plate p³, as indicated particularly in Fig. 6, of the drawings.

The face of the valve v, is formed with an annular recess v², for the reception of a ring v³, of fibrous material for direct contact with the seat c', as in Fig. 4, said contact ring v³, being held in place by a nut n, screwing onto the threaded end of the central stud v⁴, of the valve v. Obviously by this form and construction of valve the wear of use will be only on the fibrous contact ring v³, which may be readily replaced on occasion upon the removal of the stem S, without disturbance or renewal of the tubular casing C, and seat c'.

Our new valve and the mounting thereof is designed especially to replace the old type of needle point push valve heretofore positioned directly within the steam chest of the presshead and to overcome the objections thereto, said old type of valve and casing having to be removed bodily for replacement, whereas by our novel construction and arrangement of parts, renewal of the fibrous contact ring v³, may be effected without disturbing the tubular casing C, and its valve seat c'. Furthermore, we eliminate internal spring pressure, a source of serious trouble in the old push valve incidental to spring deterioration by exposure to heat and contact with steam. An additional advantage attained by our valve and mount is the prevention of contact of steam with the valve stem packing, heretofore a source of trouble in the old forms of valve installation for this purpose, necessitating frequent renewal.

What we claim as our invention and desire to secure by Letters Patent, is:—

1. A valve for use in a clothes steaming and pressing apparatus, comprising a tubular valve casing, a transverse partition in and integral with said tubular casing, said partition being formed with a valve seat and steam passages, a valve engageable with said valve seat for shutting off flow of fluid through said passages, and means for operating said valve, comprising a screw-threaded rotative stem swivel-connected with said valve, as and for the purpose set forth.

2. A valve for use in a clothes steaming and pressing apparatus, comprising a tubular valve casing, a transverse partition in and integral with said tubular casing, said

partition being formed with a valve seat and steam passages, a valve engageable with said valve seat for shutting off flow of fluid through said passages, and means for operating said valve, comprising a screw-threaded rotative stem swivel-connected with said valve, said valve stem being formed with an annular sealing collar for contact with an opposed surface when the valve is open, substantially as set forth.

3. A valve for use in a clothes steaming and pressing apparatus, comprising a tubular valve casing, the portion of said tubular casing adapted to extend above the press-head of the said apparatus being screw-threaded peripherally for engagement with a binding nut, said binding nut and a packing ring adapted to be interposed between it and the presshead, a transverse partition in and integral with said tubular casing, said partition being formed with a valve seat and steam passages, a valve engageable with said valve seat for shutting off flow of fluid through said passages, and means for operating said valve, substantially as and for the purpose set forth.

4. A valve for use in a clothes steaming and pressing apparatus, comprising a tubular valve casing, a transverse partition in and integral with said tubular casing, said partition being formed with a valve seat and steam passages, a valve engageable with said valve seat for shutting off flow of fluid through said passages, means for operating said valve comprising a screw threaded rotative stem swivel-connected therewith, a female screw threaded cap member rigidly attached to the upper extremity of said tubular casing and functioning as a nut for the

operative screw on the valve stem, and an annular shoulder on said valve stem contacting with said cap nut member when the valve is open, substantially in the manner and for the purpose set forth.

5. A valve for use in a clothes steaming and pressing apparatus, comprising a tubular valve casing, a transverse partition in and integral with said tubular casing, said partition being formed with a valve seat and steam passages, a valve engageable with said valve seat for shutting off flow of fluid through said passages, means for operating said valve comprising a screw threaded rotative stem swivel-connected therewith, a female screw threaded cap member rigidly attached to the upper extremity of said tubular casing and functioning as a nut for the operative screw on the valve stem, and an annular shoulder on said valve stem contacting with said cap nut member when the valve is open, together with a handle attached to said valve stem, and a retractile spring attached to said handle and to a bracket arm affixed to the valve casing, as and for the purpose set forth.

6. A valve for use in a clothes steaming and pressing apparatus, comprising a tubular valve casing having a transverse partition with a port therein, and a ported valve seat above the same having communication with said port and vertical outlets through said partition and into said casing below said partition, and a valve in said casing above said seat and having a detachable ring adapted for engagement with the upper face of the partition-seat only.
